ROBERT B. WILLIAMSON, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

WINDING FOR DYNAMO-ELECTRIC MACHINES.

1,400,336.

Specification of Letters Patent. Patented Dec. 13, 1921.

Application filed December 1, 1916. Serial No. 135,082.

To all whom it may concern:

Be it known that I, ROBERT B. WILLIAMSON, a citizen of the United States, residing at Milwaukee, in the county of Milwaukee and 5 State of Wisconsin, have invented a certain new and useful Improvement in Windings for Dynamo-Electric Machines, of which the following is a specification.

This invention relates to an improved design 10 of windings for dynamo-electric machines.

In the design and construction of certain types of dynamo-electric machines, especially alternating current machines of comparatively 15 large size, in order to reduce to a low value eddy currents which may be induced in a winding made up of a single conductor of comparatively large cross-sectional area, the tendency toward the production of such 20 currents resulting from the difference in amount of magnetic flux surrounding different portions of the conductor, it may be desirable to split the conductor into a plurality of branches insulated from each other within 25 the slots of the machine. Again, where the conductor in the slot is fairly deep, that is, in a radial direction, different portions or strata of the conductor are affected to different extents by leakage flux, 30 the portions of the conductor nearer the closed end of the slot consequently having greater reactance, the result being that current may circulate through the several parallel connected portions of the conductor and 35 the effective current may be crowded to one portion of the conductor so that that portion of the conductor nearer the open end of the slot may carry more than its proper share of the total current.

With the conductor in the slots divided into several insulated branches to avoid or materially reduce eddy current effects, unless these branches are maintained separate throughout the entire winding or, at least, 45 a section of the entire winding, and means are provided for equalizing the impedances of the branches, the effects of circulating currents and, generally, the unequal distribution of current in the several branches of 50 the conductor may be such as to very noticeably affect the heating and general efficiency of the machine. This will be apparent when it is considered that, with these branches maintained separate and insulated one from

another throughout their length, there may 55 exist the condition wherein one of the branches is carrying current considerably above a certain average value and another branch carrying current considerably below the same value, which value would, under ordinary circumstances, be that which either branch could carry without undue heating during the operation of the machine. This unequal division of the current in the several branches is wholly undesirable for 60 it increases the heat losses of the winding, these losses being a minimum when the current in the several branches is proportional to the ohmic resistances of the branches. In addition to this, it will be apparent that 65 greatest economy in copper is realized when all parts of the conductor are worked at the maximum safe current density.

In accordance with this invention, the conductor of which the winding is constituted 75 is divided into two or more branches in the slots of the core and means are provided for causing the current in the several branches to divide proportionally, thus, in addition to reducing eddy current losses to a low figure, 80 avoiding losses due to circulating currents when these branches are connected together at their ends, and, generally, insuring that the conductors of the several branches are worked at the same current density.

The invention is carried out as to its general features by dividing the conductor into several parallel branches fully insulated one from another throughout the length of the conductor, and by adding an artificial reactance to that one of the several parallel circuits which may have the least reactance due to the position of portions thereof relative to the core, this addition of reactance being made preferably outside of the core and in 95 the end turns or, as it may be desirable, in the leads when the entire winding or one phase thereof is divided into several parallel branches disposed in the same slots and insulated from each other throughout.

It is an object of this invention to provide an improved winding construction for dynamo-electric machines.

It is a further object to provide an improved winding for dynamo-electric machines wherein the conductor of which the winding is made up is divided into a plurality of parallel connected branches insu-

lated one from another and the current is caused to divide between the several branches in the desired proportion.

These and other objects are attained by this invention, the various novel features of which will appear from the description and drawings, disclosing one embodiment of such invention, and will be particularly pointed out in the claims.

10 In the accompanying drawings:

Figure 1 is a development of a portion of a winding of the distributed type for use in the slots of the core of a dynamo-electric machine, and embodying features of this invention.

Fig. 2 is a broken sectional view of a core showing portions of a winding of the two layer type disposed in a slot of the core, each layer of the winding being made up of two parallel connected, insulated branches.

Fig. 3 is an end view showing the connections between the several branches of the winding of Fig. 1.

Fig. 4 is a broken end view of a core showing portions of the winding of Fig. 1 in position in the slots of the core.

Figs. 5 and 6 are diagrammatic views illustrative of the general principle involved in the invention.

30 In the drawings, the general invention is shown applied to an ordinary form of winding for dynamo-electric machines. For purposes of illustration, this winding may be considered as a portion of a two-layer winding of the stationary armature of an alternating current generator. The stationary core 10 is provided with radial slots 12. A portion of one layer of the winding is disposed in the slots adjacent the air gap and a portion of a second layer 14 of the winding is disposed at the inner ends of the slots, a wedge 15 being used to hold the winding elements in position. The conductors forming the several layers of the winding are divided into a plurality of branches, the winding element 13 being divided into two branches 16 and 17 insulated one from another and insulated from the layer of winding 14, and being preferably of the same cross-sectional area. As illustrated generally in Figs. 2, 3 and 4, these several branches may be maintained insulated one from another throughout several turns of the winding, or any section of the winding, or even 45 throughout the entire winding of a single phase. The section of the winding illustrated may be considered as a portion of a single phase winding.

Considering a slot-occupying portion of the conductor or winding element 13, it will be apparent that the leakage flux between adjacent teeth is different for the several radially superposed branches 50, 51, the branch 51, due to its being effectively more remote as a whole from the air-gap, links

with a greater amount of leakage flux than the branch 17. Consequently, the branch 16 will have greater reactance than the branch 17, the effect of this being that the current through the winding element 13 divides unequally, even though the ohmic resistances of the several branches are equal, the greater amount of current crowding through the branch 17. Were this same condition present in each of the slots occupied by the portions of the winding element 13 connected in series, that is, if no provision were made for shifting the relative positions of the several branches in the slots to counteract the increased reactance of certain portions due to leakage flux, the effect of the increased reactance of the branch 16 would be very noticeable and the current in the branch 17 would be considerably greater than that in the branch 16. The $I^2 R$ losses in the winding would then be considerably greater than if each of the branches carried the same amount of current.

Considering the illustrative showing of Fig. 5, the conductors 16_n and 17_n may represent conductors of the same ohmic resistance insulated one from another and carry-current between the terminals t_1 and t_2 . However, assume that, due to some reactive effect on the branch 16_n, instead of currents of the same value flowing in the two branches, the current flowing in branch 16_n is considerably less than that flowing in the branch 17_n. Now, in order to cause the current to divide equally between the branches 95 an artificial reactance must be inserted in the branch 51, this reactance being designated R_p and being of such dimensions as to cause the current to divide in the proper proportion between the several branches. 100

To illustrate the principle involved, consider that normally, with the parallel connected branches of the same equivalent resistance, say 1 ohm, each branch carries 50 amperes, under which circumstances the 110 total $I^2 R$ losses are $50^2 \times 1 = 2,500$ watts for each branch, or a total of 5,000 watts; whereas, if, for some reason, the total current be caused to divide unequally between the two branches, say 60 amperes in one 115 branch and 40 in the other, the total $I^2 R$ losses would be $60^2 \times 1 = 3,600$, plus $40^2 \times 1 = 1,600$, or a total of 5,200 watts. This particular unequal division of the total current through the several branches gives an 120 increased heat loss of 200 watts. Likewise, this increase in total $I^2 R$ loss would vary as the square of the difference between currents in the two branches.

This principle is illustrated further in 125 Fig. 6 wherein the conductive element between the terminals t_3 and t_4 is divided into three branches, 18, 19 and 21. It may be assumed that, due to certain conditions present, the current in the several branches 130

has a tendency to divide unequally, and that the branch 18 tends to carry the greatest part and the branch 21 the least. In order to cause the current to divide equally between the several branches artificial reactances R_s and R_v , having no effect on the ohmic resistances, are inserted in the branches 19 and 18, respectively, these reactances being of such value as to cause a proper division of the current between several branches and a reduction to a minimum of the heat losses in the conductive path between terminals t_3 and t_4 .

In general accordance with the principle outlined in the above explanation, assume that, when no special provisions are made to prevent it, the current divides unequally between the branches 16 and 17 of the conductor 13, the branch 17 carrying the greatest part of the total current due to the greater reactance of the branch 16 on account of the effect of leakage flux in the core. Of course, in the specific arrangement illustrated, wherein the section of a phase winding shown is made up of three coils 24, 25, 26, one side of each coil being at the outer part of one of the slots 12_a, 12_b, 12_c, and the other side of each coil at the inner part of one of the slots 12_d, 12_e, 12_f, as indicated in Figs. 1, 2, 3 and 4, the reactive effects due to leakage flux on the several branches of the conductive element of the winding may be balanced to some extent; nevertheless, there may be considerable difference in the current flowing in the two branches 16, 17, and, hence, the general principle of this invention is applicable to this condition as well as to the case where the branches are insulated throughout and so disposed in the slots of the core that the unbalancing effect in the portions located in the several slots is cumulative or where the result is one of general unbalance between the several branches.

The type of winding illustrated in Figs. 1, 2, 3 and 4 is an ordinary one of the two layer type, the section of the winding shown comprising the three coils 24, 25, 26, each being made up of a conductive element divided into two parallel branches insulated throughout the length of the coil and joined together at their end portions. The circuit through the several coils of the winding sections shown may be traced from the terminal T_1 , where the ends of the several branches 16, 17 are brought out and connected together by a conductive clip 28. Throughout the entire length of the several coils the branches 16, 17, are insulated one from another. From the terminal T_1 , the coil 24 extends through the outer part of the slot 12_a, making a 180 degree bend at the U-turn at the rear end of the core and returning through the slot 12_a with the branch 16 at the bottom or inner end of the slot. The

ends of the several branches of each coil are spaced apart, as indicated generally in Figs. 1, 3 and 4, to facilitate connection with the proper branches of other coils. The coils 25 and 26 are similarly arranged in the slots 12_b, 12_c and 12_e, 12_f, respectively. The terminals of the branches 16 and 17 of the several coils are designated 16_a, 16_b, 16_c, . . . 16_f and 17_a, 17_b, . . . 17_f, the subscript in each case denoting the slot from which the terminal emerges at the front side of the core, as indicated in Figs. 1 and 3. The terminals are brought out separately, with a terminal of one branch of one coil radially aligned with a terminal of a like branch of an adjacent coil, so that the several branches may be readily connected in series throughout the several coils while maintaining the branches 16, 17 fully insulated throughout the entire length of the phase winding or section thereof.

The manner of connecting like branches of the several coils in series is fully disclosed in Figs. 1, 3 and 4, wherein the terminal 17_b of the coil 25 is radially aligned with the terminal 17_a of the coil 24, the two being connected by a conductor clip 29, the terminal 16_b of the coil 25 is brought out in radial alinement with the terminal 16_a of the coil 24 and is connected thereto by a conductive clip 31, the terminal 17_c of the coil 26 is brought out in radial alinement with the terminal 17_a of the coil 25 and is connected thereto by a conductive clip 32, and the terminal 16_c of the coil 26 is brought out in radial alinement with the terminal 16_a of the coil 25 and is connected thereto by a conductive clip 34. The terminals 16_f and 17_f of the branches 16 and 17 of the coil 26 are connected together by a clip 35 which is in turn connected to the terminal T_2 .

It will be noted that, if the winding is traced from one of its terminals, as T_2 , to the other terminal, the superposed branches thereof are radially transposed as the winding progresses from each active zone to another. The result is that the branch 16 has, in the instance disclosed, three conductors 16_f, 16_e, 16_d located at the very bottom of the respective slots and three conductors 16_c, 16_b, 16_a located at the very top of the respective slots, while the branch 17 has three conductors 17_f, 17_e, 17_d and three conductors 17_c, 17_b, 17_a located respectively in the third and second layers, counting from the air gap, in the respective slots. In general, then, by reason of the better magnetic path around the conductors 16_f, 16_e, 16_d, the branch 16 will have the higher inductance.

While the described relative arrangement in the core slots of the several branches 16, 17 of the conductive element of which the winding is made up is such as may ordinarily produce fairly good results in balancing the reactive effects due to leakage flux,

nevertheless, even with this arrangement, it is the case quite often that the current does not divide equally between the several branches and, hence, there are present un-
5 called for heat losses. It is considered that the latter is the actual condition present in the case described and illustrated, it being assumed that the impedance of the branch
10 16, due to the effects of leakage flux, is greater than that of the branch 17, and, accordingly, that the branch 17, made up of portions of the coils 24, 25 and 26, unless provisions are made to prevent it, carries a greater part of the total current than the
15 branch 16, also made up of portions of the coils 24, 25, 26. In order to balance the impedances of the two branches 16, 17, an artificial reactance 37, preferably having no effect as an ohmic resistance, is associated
20 with the branch 17, this reactance being preferably in the form of a closed or partly closed ring of magnetic material, and being of such proportions as to render the total impedance of the branch 17 the same as that
25 of the branch 16 in which leakage flux ex-
ercises a greater reactive effect. This react-
ance 37 is preferably associated with a ter-
minal portion of the branch 17, indicated in
30 Fig. 1 as being associated with the terminal
17.

While, in the case illustrated, the tendency toward unbalanced currents in the several branches or strata of the conductive element of which the winding is constituted
35 is counteracted to a considerable extent by reversal of the relative positions of the branches in the several slots, nevertheless, the general principle of this invention can ordinarily be utilized, even in this case, to a
40 considerable advantage in improving the operating characteristics of the machine. Of course, the utility of the invention is proportionately greater in cases where the design of the machine is such that the several
45 parallel branches or strata are not so dis-
posed throughout their full length that the reactive effects of leakage flux are counter-
acted in a substantial part. Likewise, it will be apparent that, as to certain features of
50 the invention, advantages are present inde-
pendently of whether the parallel connected branches of the conductive element are main-
tained separate and insulated one from an-
other throughout only single slot-occupying
55 portions or throughout the entire winding or a substantial portion thereof. In fact, advantages may be derived from the use of this invention in any case where there is a tendency for the current to divide unequally
60 between several strata or branches of the conductive element, independently of whether provisions, such as the reversal of the relative positions of portions of the conductive element in the several slots, are

made for neutralizing in part the reactive 65 effects due to leakage flux.

It should be understood that it is not de-
sired that the invention as claimed be limited to the exact details of construction shown and described, for obvious modifica-
70 tions will occur to a person skilled in the art.

It is claimed and desired to secure by Letters Patent:

1. In a dynamo electric machine a core provided with slots, an induced winding, 75 having end turns, comprising a plurality of comparatively heavy branches of substantially the same ohmic resistance and different inductive resistance radially superposed in the same slot, said branches being elec- 80 trically connected together only at the re-
spective ends thereof, and means other than the relative disposition of the branches as-
sociated with end turns of said winding for equalizing the impedance of the several 85 branches.

2. In a dynamo electric machine, a core provided with slots, an induced winding, having end turns, comprising a plurality of parallel connected comparatively heavy 90 branches in the same slot, and artificial re-
actance-means associated with end turns of said winding and with the circuit of a branch or branches upon which leakage flux has less reactive effect than on another 95 branch.

3. In a dynamo electric machine, a core provided with slots, an induced winding, having end turns, comprising a plurality of parallel connected comparatively heavy 100 branches in the same slot radially super-
posed therein, and artificial reactance-means associated with end turns of said winding and with the circuit of a branch or branches upon which leakage flux has less reactive 105 effect than on another branch.

4. In an alternating current dynamo elec-
tric machine, a core provided with slots, an induced winding, having end turns, comprising a plurality of parallel connected 110 comparatively heavy branches in the slots, and means, other than the relative disposi-
tion of the branches, associated with the end turns of said winding for insuring the current divides so as to secure uniform current 115 density in the branches.

5. In an alternating current dynamo elec-
tric machine, a core provided with slots, an induced winding, having end turns, comprising a plurality of parallel connected 120 comparatively heavy branches in the slots, and means, other than the relative disposi-
tion of the branches, associated with the end turns of said winding and with the branch disposed effectively nearest the air 125 gap of the machine for insuring the current divides so as to secure uniform current den-
sity in the branches.

6. In an alternating current dynamo-electric machine, a core provided with slots, a winding comprising a plurality of parallel connected branches radially superposed and insulated one from another within said slots, and means inductively associated with an extending end portion of the branch that is subject to less reactive effects due to its position relative to the core, said means being effective to cause the current to divide so as to insure uniform current density in the several branches. 35
7. In a dynamo electric machine having a core, a winding including a plurality of form-wound coils disposed on said core, said winding comprising a plurality of radially superposed branches electrically connected together only at the respective ends thereof, said coils having U-bend end-connectors 40
- 10 whereby the induced portions of said branches are transposed radially as the winding progresses from one side of a coil to the other, and means for connecting the end of one coil to the beginning of the next 45
- 15 20 coil so that as the winding progresses from one coil to the next the branches are radially transposed whereby the impedance of said branches is practically equalized. 50
- 25 30 8. In a dynamo-electric machine having a winding with a plurality of radially su- 55
- perposed branches connected at the respective ends thereof, means for practically equalizing the impedance of said branches including the radial transposition of said branches as the winding progresses from one active zone to another, and means for introducing an additional impedance in the branch having the lowest impedance for the purpose of substantially equalizing the impedance of the branches. 40
9. In a dynamo electric machine, the combination with a winding therefor having a plurality of parallel connected branches, of means associated with a branch having a lower reactance than another branch for introducing an additional reactance in said branch without altering the ohmic resistance of said branch. 45
10. In a dynamo electric machine, the combination with a winding therefor having a plurality of parallel connected branches of a ring-like member of magnetic material associated with a branch having a lower reactance than another branch, whereby an additional reactance is introduced in said branch without altering the ohmic resistance of said branch. 50

In testimony whereof, the signature of the inventor is affixed hereto.

ROBERT B. WILLIAMSON.
